UNITED STATES PATENT OFFICE.

EDMUND H. SAWYER, OF LEXINGTON, MASSACHUSETTS.

SHUTTLE AND QUILL FOR NARROW-WARE LOOMS.

SPECIFICATION forming part of Letters Patent No. 748,887, dated January 5, 1904.

Application filed November 9, 1903. Serial No. 180,307. (No model.)

To all whom it may concern:

Be it known that I, EDMUND H. SAWYER, a citizen of the United States, residing at Lexington, in the county of Middlesex and Commonwealth of Massachusetts, have invented an Improvement in Shuttles and Quills for Narrow-Ware Looms, of which the following description, in connection with the accompanying drawings, is a specification, like letters on the drawings representing like parts.

My invention aims to improve shuttles and their quills for use in looms for weaving tapes and other fabrics to which they may be adapted.

15 Prior to my invention shuttles for looms of this character have usually been provided with quills of cylindrical formation and having a length much greater than their diameter and arranged to revolve during unwinding of the shuttle-thread about axes which are respectively parallel with the lines of travel of the shuttles. Shuttle-quills of this shape will ordinarily contain thread enough for less than one-half day's operation of a loom, thus involving waste of time for renewals in the midst of each working part of a day. Furthermore, because of the relatively great lengths of the quills the threads in drawing therefrom through the single eyes 20 with which the shuttles are respectively provided are caused to whip laterally back and forth through considerable distances, resulting in greatly-varying tensions and also tending to break or snap the threads. My invention overcomes these objections by providing 25 for quills which are of much greater diameter than the lengths thereof, so that they rest flatwise in the shuttles and revolve about axes which are perpendicular to the lines of travel of the shuttles. Quills so wound will carry in the same size shuttles much more and usually twice the length of shuttle-threads as compared with the former quills, above referred to, and have the added advantage that the threads are drawn off more 30 nearly centrally through the shuttle-eyes at all times.

To enable my invention to be understood, I have illustrated one embodiment thereof in 35 the accompanying drawings, to which reference may be had.

In the drawings, Figure 1 in top or plan view shows a shuttle equipped with a quill in

accordance with my invention; Fig. 2, a right-hand edge view of Fig. 1; Fig. 3, a front edge view of Fig. 1, and Figs. 4 and 5 details illustrating in cross-section two forms of quills which may be used by my invention.

In the particular embodiment of my invention selected for illustration herein and shown in the drawings the shuttle *a* of general semicircular contour is provided along its straight edge and at one side with a usual raceway *a'*, in which travels the race-block upon the lay. At its opposite side and also adjacent its straight edge the shuttle is provided with a countersunk rack *a*², which meshes with usual driving-pinions also upon the lay and not herein shown. The semicircular edge of the shuttle is thinned gradually from its opposite sides, as best shown at *a*³, Fig. 2, to approximate the angular separation of the warp-threads in shed formation, between which the shuttle is required to be reciprocated.

The shuttle is provided with a usual semicircular opening *b*, and into this opening extend at opposite sides of the shuttle two resilient or spring-like arms *b'*, provided at their free ends with facing knobs or projections *b*², adapted to receive and hold rotatively between them the quill-spindle upon which the quill is wound.

The quill may be built up in any suitable cross-sectional form—such, for instance, as illustrated in Figs. 4 and 5—so long as its diameter greatly exceeds its length or thickness and so long as the successive windings of the thread are so arranged or traversed one relative to another that the quill or thread mass is rendered self-supporting without requiring the use of spool heads, ends, or cups for its support. While the quill may be rectangular in cross-section, as in Fig. 4, I prefer to build up a quill which in cross-section shall show a gradual taper or reduction from a proper point removed from the axis and toward the periphery thereof, so that when in position in the shuttle, as shown in Figs. 2 and 3, the general shape of the quill will approximate to the taper of the shuttle itself. The quill-spindle *c* may be tubular, as usual, or otherwise suitably formed to receive the holding-knobs *b*² in a manner that will permit the quill to revolve as the shuttle-thread is drawn therefrom.

The winding of the quill may be accom-

- plished in any suitable manner, as by usual traverse winding means of the "universal" type or in any other manner so long as the quills are self-contained and self-supporting 5 without the use of opposing cups or holders.
- The shuttle is provided with one or more tension members *d*, which press upon the periphery of the quill, and also, if desired, with one or more tension members, as *d'*, which 10 press upon the side of the quill, all for the purpose of placing the quill under desired or necessary tension to prevent it from unwinding too easily during reciprocations of the shuttle should the holding-arms be insufficient for this purpose.
- If desired, suitable guide or protection wires *e* may be provided spanning the exposed portions of the quill at opposed sides of the shuttle near the thin edge thereof for the purpose 15 of separating the warp-threads or preventing the latter from coming into too firm frictional contact with the quill during passage of the shuttle through the shed.
- A quill built up as hereinbefore described 20 and of which the best example thereof now known to me is herein shown and particularly described—namely, with a diameter which greatly exceeds its length or thickness—will contain about twice the length of thread as 25 compared with the present quills, which have a length greatly in excess of the diameter and where its diameter is of the thickness of the shuttle, as is the thickness or length of the quill in my present invention. Thus without 30 increasing the thickness of the shuttle I substantially double the length of time during which the shuttle will operate without requiring stoppage for renewal of the quill first.
- Furthermore, with my present invention 35 the lateral traverse of the shuttle-thread in traveling from edge to edge of the quill is hardly one-third of the length of traverse from edge to edge of the quills as at present used, so that the draft of thread is much more 40 direct, permitting much more uniform tension and greater freedom from breakages due to twitching or whipping of the thread.
- My invention is not limited to the particular embodiment thereof here shown and described, but may be varied within the spirit 45 and scope of the invention gathered from the claims.
- I claim—
1. A shuttle provided with means to hold a self-supporting quill with its axis perpendicular to the line of travel of the shuttle.
  2. A flat shuttle provided with means for holding flatwise therein a flat self-supporting quill of a diameter greatly in excess of its depth or thickness.
3. A narrow-ware shuttle provided with a quill-opening and quill-holding fingers projecting thereinto constructed to embrace between them and support a self-supporting quill and arranged with their quill-holding portions opposed to each other in a line perpendicular to the line of travel of the shuttle.
4. A flat narrow-ware shuttle provided with means for holding a flat self-supporting quill flatwise in said shuttle and quill-tension means adapted to press directly upon the thread mass.
5. A flat narrow-ware shuttle provided with means for holding a flat self-supporting quill flatwise in said shuttle and quill-tension means adapted to press directly upon the periphery of the thread mass.
6. A flat narrow-ware shuttle provided with means for holding a flat self-supporting quill flatwise in said shuttle and quill-tension means adapted to press directly upon the flat side of the thread mass.
7. The combination with a flat shuttle made tapering toward one edge thereof, and adapted to hold a flat self-supporting quill arranged flatwise with and in said shuttle and also made tapering toward its periphery.
8. A shuttle provided with means for holding a flat self-supporting quill flatwise in said shuttle and quill-protecting means spanning the said quill or a portion thereof.
9. A narrow-ware shuttle having an opening therethrough, means to confine in both directions in said opening a self-supporting quill with its axis perpendicular to the line of travel of the shuttle, and shuttle guiding and driving means arranged at one side of said opening.
10. A narrow-ware shuttle having an opening therethrough, means to confine in both directions in said opening a self-supporting quill with its axis perpendicular to the line of travel of the shuttle, shuttle guiding and driving means arranged at one side of said opening, and protection means spanning said opening adjacent the edge of the shuttle opposite the driving and guiding means.
- In testimony whereof I have signed my name to this specification in the presence of two subscribing witnesses.
- EDMUND H. SAWYER.
